US00D759728S

(12) **United States Design Patent**
Byrne et al.

(10) **Patent No.:** US D759,728 S
(45) **Date of Patent:** ** Jun. 21, 2016

(54) **POWER END FRAME SEGMENT**

(71) Applicant: **S.P.M. Flow Control, Inc.**, Fort Worth, TX (US)

(72) Inventors: **Joseph H. Byrne**, Hudson Oaks, TX (US); **Jacob A. Bayyouk**, Richardson, TX (US); **Chandu Kumar**, Fort Worth, TX (US)

(73) Assignee: **S.P.M. Flow Control, Inc.**, Fort Worth, TX (US)

(**) Term: **15 Years**

(21) Appl. No.: **29/534,091**

(22) Filed: **Jul. 24, 2015**

(57) **CLAIM**

The ornamental design for a power end frame segment, as shown and described.

DESCRIPTION

FIG. 1 is a front perspective view of a power end frame segment;

FIG. 2 is a front view of the power end frame segment;

FIG. 3 is a rear view of the power end frame segment;

FIG. 4 is left side view of the power end frame segment;

FIG. 5 is a right side view of the power end frame segment;

FIG. 6 is a top view of the power end frame segment; and,

FIG. 7 is a bottom view of the power end frame segment.

The broken lines in FIGS. 1 through 7 form no part of the claimed design.

1 Claim, 5 Drawing Sheets
